TRAVELING PLATFORM CONVEYER

Furman S. Abbott, Montclair, N. J.

Application January 25, 1947, Serial No. 724,372

6 Claims. (Cl. 198—138)

1

The present invention relates to conveyors of the type disclosed in the Bausman et al. Patent No. 1,023,103 of April 9, 1912, which is particularly adapted to move a plurality of successively arranged platforms in two lateral banks.

The general object of the present invention is to provide such a conveyor which is characterized by a plurality of successively arranged platforms disposed in two laterally extending banks and simultaneously movable first along one level, then across to another level, along the second level and finally back to the first level, in which means are provided for effective support of both ends of each platform substantially at all times during its travel and in any position whereby the apparatus is efficiently adapted to automobile or car storage, in parking lots, and in buildings and the like.

A more specific object of the invention is to provide such conveyor apparatus wherein the successively arranged platforms are so supported at all times during transport and in all positions as to make the device efficiently useful in the support and handling of very heavy objects, such as automobiles, and which, for this purpose, is characterized by separate track-riding means mounted on opposite ends of each platform with separate transfer track means at both ends of the apparatus respectively to cooperate with the separate track-riding means to assure efficient support and guidance in transfer of the platforms from lateral track means at one level to lateral track means at another level.

Another object of the present invention is to provide in such conveyor apparatus certain switch means effectively permitting the employment of dual transfer track means at both ends of the apparatus for continuous support and guidance of the platform-supporting track-riding means at both ends of each of the platforms, while effectively permitting those at the same ends of each platform to follow one path, and those at the other ends of the platform to follow another path with continuous support of both sets of track-riding means.

Still another object of the present invention is the provision in such conveyor apparatus of certain transfer track means which efficiently accomplishes the continuous platform support and effective guidance desired.

A further object of the present invention is to provide for such a conveyor device unique switch means adapted to the structures of different embodiments whereby the desired operation may be effectively accomplished.

2

Other objects of the invention will in part be obvious and will in part appear hereinafter.

The invention accordingly comprises the features of construction, combination of elements and arrangement of parts, which will be exemplified in the construction hereinafter set forth, and the scope of the invention will be indicated in the claims.

For a fuller understanding of the nature and objects of the invention, reference should be had to the following detailed description taken in connection with the accompanying drawings, in which:

Fig. 1 is a longitudinal elevational section of one embodiment of the conveyor apparatus of the present invention showing the mechanism thereof mounted in proper position with respect to a ground line diagrammatically indicated and above which the entire structure is mounted;

Fig. 2 is an enlarged top-plan view, with parts broken away and omitted, of the apparatus shown in Fig. 1;

Fig. 3 is a longitudinal elevational section, with parts broken away and omitted, showing one end of a modified form of the apparatus depicted in Fig. 1 as adapted for mounting below the ground line in a recess, the adjacent soil being diagrammatically indicated;

Fig. 4 is a top-plan view, with parts broken away and omitted, of a further modification of the apparatus shown in Fig. 1;

Fig. 5 is a transverse elevational section of the apparatus, with parts broken away, shown in Fig. 4, taken substantially on line 5—5 of Fig. 7, wherein a longitudinal elevational section is shown;

Fig. 6 is a transverse elevational section, with parts broken away and in section, taken substantially on line 6—6 of Fig. 7;

Fig. 7 is a longitudinal elevational section, with parts broken away, of the apparatus shown in Figs. 4, 5 and 6; and

Fig. 8 is a sectional view taken substantially on line 8—8 of Fig. 7, showing more of the track structure than that indicated in the left-hand half of Fig. 7.

In the drawings, similar numerals identify similar parts throughout and as will be noted from Figs. 1 and 2, an embodiment of an apparatus of the present invention may comprise an upper laterally extending track means 10 and a lower laterally extending track means 11. Each of the track means 10 and 11 may comprise a pair of transversely spaced apart rails such as 12, 12 and 13, 13 respectively, as may be desired.

Track means 10 and 11 are adapted to guide and support therefrom a plurality of platforms 14—14 each suspended from track-riding or rail-riding means 15 and 16. Accordingly, due to the suspension support of the platforms 14—14, the upper and lower lateral track means 10 and 11 are mounted in elevated positions above the ground line indicated diagrammatically at 17, as shown in Fig. 1, with the suspended platforms 14—14 in the lower bank adapted to be located successively at a receiving station, such as at 18, indicated at the left-hand end of the apparatus and shown in Fig. 1 near the ground surface so as to permit an automobile to be driven onto each platform.

Each platform 14 preferably comprises a pair of transversely spaced apart channel members 19, 19 as shown in Fig. 2 which are adapted to receive the four wheels of an automobile. Each channel member 19 is supported in the vicinity of its ends from one each of the track-riding means 15 and 16 by any suitable means such as suspension members or cables 20—20. Preferably, in the embodiments shown in Figs. 1 and 2, the track-riding means 15 and 16 are of similar construction and each may be in the form of a truck. The rail-riding means 15 comprises a transverse axle 21 supporting the cables 20—20 connected to platform members 19, 19, with wheels 22, 22 rotatably mounted thereon to ride upon the rails 12, 12 and 13, 13. The rail-riding means 16 comprises a transverse axle 23 to which cables 20—20 are connected for support of the other end of the channel members 19, 19, and similar wheels 22, 22 are mounted thereon with the ends of that axle extending beyond those wheels to carry anchoring clamps 24, 24. Thus the rail-riding means 15—15 constitute one set thereof and the rail-riding means 16—16 constitute another set thereof with the latter provided with clamps 24—24 to fasten them to any suitable flexible endless means, such as a pair of endless cables 25, 25. As a result endless cables 25, 25 will carry around with them the set of rail-riding means 16—16 and in certain positions, as hereafter explained, will support those rail-riding means. The other set of rail-riding means 15—15 are unconnected to the cables 25, 25.

A pair of pulley wheels 26, 26 are rotatably supported on the left-hand end of the apparatus as shown in Figs. 1 and 2, and a similar pair 27, 27 are rotatably supported at the right hand end of the apparatus with the endless cables 25, 25 trained about those pulley wheels. At least one of those pulley wheels, such as the one at 26, shown in Fig. 1, and in the upper left-hand corner of Fig. 2, is driven by any suitable means such as a sprocket 28 and driving chain 29. The sprocket 28 may be fixed upon shaft 30 rotatably mounted through bearing support 31 with its inner end fixedly carrying the pulley wheel 26. The other pulley wheel 26 may, if desired, be driven in similar manner. Similar supporting bearings 31—31 carry the stub shafts for the remaining pulley wheel 26 and the two pulley wheels 27, 27.

The driven shaft 30 also carries a sprocket 32 fixed thereto about which is trained a driving chain 33, in turn trained about another sprocket 34 fixed to a stub shaft 35 carried by a supporting bearing 36, and this structure is preferably duplicated at both ends of the apparatus and on both sides thereof, as shown in Fig. 2. Stub shafts 35, 35, at either end of the apparatus, have

fixed thereto arms 37, 37 adapted to engage beyond and behind the transverse axle 21 of each rail-riding means 15, so as to lift the latter at the left-hand end of the apparatus and lower it at the right-hand end of the apparatus at substantially the same speed as the rail-riding means 16 of the same platform 14 is lifted and lowered between the upper and lower lateral track means 10 and 11. Of course, for this purpose, other endless means similar to the cables 25, 25 to which transverse axles 23—23 are anchored may be employed in lieu of the operating arms 37—37 and their driving mechanisms. Such means may comprise endless chains and in such case the wheels 26, 26 and 27, 27 will be sprockets.

At each end of the apparatus shown in Figs. 1 and 2 are provided two inner and outer transfer track means, respectively to guide and support the sets of rail-riding means 15—15 and 16—16 as the latter are transferred between the upper and lower lateral track means 10 and 11. At the left-hand end of the apparatus the outer transfer track means 38 may comprise upwardly sloped continuations 39, 39 of the lower rails 13, 13 with those continuations preferably being upwardly curved and extending at least to the vicinity of the mid-plane of the apparatus which passes through the axes of the stub shafts 30—30 and 35—35. Downwardly sloped (preferably curved) continuations 40, 40 of the left-hand ends of the upper rails 12, 12 extend also to the vicinity of that mid-plane and are spaced inwardly from the upwardly curved extensions 39, 39 preferably a distance a little greater than the diameter of the wheels 22, 22 carried by each of the transverse axles 23—23 of the rail-riding means 16—16. This transfer track means 38 is preferably duplicated on the right-hand end of the apparatus with the downwardly curved extensions 40, 40 spaced inwardly of the upwardly curved extensions 39, 39 a distance slightly greater than the diameters of the wheels 22—22 mounted on the transverse axles 21—21 of the rail-riding means 15—15. It will be noted from Fig. 1 that the extensions 39—39 and 40—40 of the transfer track means 38, 38 lie along arcs of circles generated about the axes of the stub shafts 30 and 35 at the left and right ends of the apparatus.

Each of the two inner transfer track means at 41, 41 comprises downwardly sloped, preferably curved extensions 42, 42 of certain portions of the upper rails 12, 12 with the one at the left-hand end lying along the arc of a circle generated about the axis of stub shaft 35 and the one at the right-hand end lying along the arc of a circle generated about the axis of stub shaft 30. Each of these inner transfer track means 41 also includes an upwardly sloped, preferably curved plate 43 and a laterally extending flat plate 44 fixed together and pivotally mounted at 45 to constitute switch means. The lateral part of each switch means may comprise a section of the upper rail 12 or may be positioned in a notch in the latter, as shown in Fig. 2, so that when swung upwardly as shown at the right-hand end of Fig. 1 a gap will be provided in the upper rail. When the switch means is in the closed position, as shown in the left-hand end of Fig. 1, the curved transfer track section 43 thereof will have its lower end located adjacent the lower rail 13. The portion between the lower end of section 43 and a point in the vicinity of the mid-plane lies along the arc of a circle generated about the axis of the stub shaft 35, with the lower end of the downwardly curved extension 42 spaced in-

wardly from that curved transfer track section a distance which is a little greater than the diameters of the wheels 22—22 fixed on transverse axles 21—21 of rail-riding means 15—15.

In operation of the embodiment of the apparatus shown in Figs. 1 and 2, for the purpose of parking and storing automobiles, the apparatus may be stopped with the platform 14 located at the approach station 18 in the position shown so that a car may be driven up on the channel numbers 19, 19 of the platform. Driving means may then be operated to cause the drive chain 29 to drive clockwise the pulley wheel 26 shown at the left in Fig. 1. By virtue of the facts that endless cables 25, 25 are tied together by transverse axles 23—23, and the lifting arms 31, 31 at the left-hand end of Fig. 1 and the lowering arms 37, 37 at the right-hand end thereof are respectively driven by sprockets 32 and 34 in turn driven by chains 33—33 from the pulley wheels 26, 26 and 27, 27, it will be seen that the endless cables 25, 25 will be moved along the upper track means 10 down about pulley wheels 27, 27 back along track means 11 and up around pulley wheels 26, 26 carrying therewith the set of rail-riding means 16—16. Of course the two endless means or cables 25, 25 may be separately and positively driven from a common power source, such as by duplicating the drive sprocket 28 and driven chain 29 on both sides of the apparatus, and with the two chains 29, 29 driven by sprockets fixed on a common driven shaft. This motion of the endless cables 25, 25 causes the successively arranged platforms 14—14 to move forward to position another platform 14 at the receiving station 18. This action may be continued until all of the platforms in the two banks are filled with cars and a driver may readily select his car for removal, although it be in any one of the numerous positions in the apparatus, by operating the latter until the platform supporting his car is moved either to the receiving station 18 or to the opposite end of the apparatus at the ground line, then to be driven off.

During such action the rail-riding means 16 at one end of the platform 14 which is supporting a particular car will be caused to move up along the curved extensions 39, 39 at the left-hand end of the apparatus and will be supported both by those curved extensions and the endless cables 25, 25 to which that rail-riding means is anchored. After rail-riding means 16 is moved up beyond the mid-plane with the wheels 22, 22 thereof passing between curved extensions 39 and 40, the wheels will then ride upon the latter to be transferred to the upper rails 12, 12. During this movement of rail-riding means 16 the trailing unconnected rail-riding means 15 will be guided up the curved section 43 of the switch means, and since the lifting arms 31, 31 travel at substantially the same angular velocity as the angular velocity of the pulley wheels 26, 26, those arms will be engaged behind transverse axle 21 of that unconnected rail-riding means and lift the latter at relatively the same speed as the connected rail-riding means 16 is lifted by the cables 25, 25. Eventually, the wheels 22, 22 of the rail-riding means 15 will pass up to roll over the downwardly curved extensions 42, 42 to be guided to the upper rails 12, 12. Then with continued motion of the cables 25, 25 the platform 14 will be carried forward along rails 12, 12 now with its unconnected rail-riding means 15 leading its connected rail-riding means 16. 75

Switch sections 44, 44 close the gaps in the upper rails 12, 12 so that there will be continual support of the rail-riding means 16.

As the platform 14 approaches the right-hand end of the apparatus a now-trailing unconnected rail-riding means 15 of a preceding platform will roll back along lower rails 13, 13 to engage the rear sides of the curved sections 43, 43 of the switch means at that end to swing them upwardly to the positions shown in Fig. 1, thereby permitting free passage of that unconnected trailing rail-riding means. This, of course, causes the switch sections 44, 44 to be swung to the lifted position shown in Fig. 1, after forward passage thereover of the then leading unconnected rail-riding means 15 of the platform under discussion, so as to permit the trailing connected rail-riding means 16 of the latter to be carried down the curved extension 42 of the inner transfer track means at the right-hand end. Eventually, after passage of the trailing unconnected rail-riding means 15 of the preceding carriage beyond the curved switch sections 43, 43, the switch will be closed, either by force of gravity or by pressure of the rail-riding means 16 of the succeeding platform under discussion against the faces of the curved sections 43, 43 so that that rail-riding means will then be guided to the lower tracks 13, 13. During this action of course the unconnected leading rail-riding means 15 travels first along the downwardly curved extensions 40, 40 of the transfer track means 38 at the right-hand end of the apparatus, and then on to the upwardly curved extensions 39, 39 to be guided to the lower rails 13, 13. During this action the lowering arms 37, 37 lead the transverse axle 21 to support the rail-riding means 15 and permit it to travel down the right-hand transfer track means at 38 at relatively the same speed as the rail-riding means 16 is lowered by cables 25, 25 down along the right-hand transfer track means at 41. Thus, it will be seen that at all times there is positive support of the means from which the platforms are suspended.

Of course, it is obvious that the apparatus shown in Figs. 1 and 2 may be operated in either direction, since the transfer track means at both ends of the apparatus are similar in structure and functioning; and, of course, suitable equivalents may be substituted for the various elements of the apparatus as desired. For example, either the transverse axles of the track-riding means or the wheels thereof may be employed to operate the switches, or separate means mounted on or to the platforms may be used to perform similar functions. Further, it should be understood that a simple modification of the apparatus can make possible operation thereof without driven means positively to lift and check the lowering of the set of unconnected rail-riding means 15—15. In such case, the transfer track means may be constructed as substantially straight line ways sloped at suitable angles with the horizontal, e.g., at 30° to 60°, and with those two transfer track means, along which the endless means or cable for carrying the set of rail-riding means 16—16 are guided, being provided at their upper and lower ends each with two pulley wheels or sprockets somewhat similar to those at 26 and 27. In such case, of course, each of the inner transfer track means will be provided with suitable switches at its top and bottom alternately to provide for entrance thereto of the rail-riding means of one set, and free passage for the rail-riding means of the other set, with the rail-

riding means of the different sets for each platform rigidly connected together by separate frame structure, or by the platform structure itself, as in the case of Fig. 3. Positive drive of the connected rail-riding means by the endless cables and guidance up the sloped transfer track means will cause the unconnected rail-riding means either to be pushed or dragged up, as the case may be, its sloped transfer track means at substantially the same rate of speed, thereby retaining the platform substantially level. At the top of the transfer track means for the unconnected set of rail-riding means a simple switch may be provided in association with an extension of the transfer track means so that the unconnected rail-riding means may be pushed or pulled up this extension past the switch which may be opened by passage of that rail-riding means, and the switch then closed, such as by force of gravity behind that rail-riding means, so that when the other-rail-riding means is then pulled forward along the upper track means by the endless cables, the unconnected rail-riding means will be supported by the switch and cross the latter to the upper track means.

The apparatus shown in Figs. 1 and 2 may be modified so that it may be mounted in a recess below the surface of the ground, as proposed in Fig. 3 wherein the ground line is indicated at 17 with a recess 46 provided therebelow. The apparatus to be mounted in the recess 46 is similar in all respects to that shown in Figs. 1 and 2 except that each channel member 19 of platform 14 is mounted above its rail-riding means 15 and 16, rather than being suspended therefrom by any suitable means, such as by standards 47, 47. As a result, each platform 14 as it is moved to the position shown in Fig. 3 is adapted to receive thereon at the ground line 17 a car which may then be carried around for underground storage or parking.

The modified form of the apparatus as shown in Figs. 4 to 8 inclusive differs chiefly from that shown in Figs. 1 and 2 in that separate pairs of transversely spaced rails are provided for the two sets of rail-riding means 15-15 and 16-16. The pairs of upper rails 12, 12 and lower rails 13, 13 are adapted for support of the connected rail-riding means 16-16 which are carried forward by the endless cables 25, 25 and another pair of upper rails 112, 112 and a second pair of lower rails 113, 113 are located inside the pairs of rails 12, 12 and 13, 13 respectively for support of the unconnected rail-riding means 15-15.

As shown in Figs. 7 and 8, the lower rails 13, 13 are constructed at the left-hand end of the apparatus, as viewed therein, similarly to their construction in the modification of the apparatus shown in Figs. 1 and 2. The upper rails 12, 12, however, continue straight through past the inner transfer track means 41 at the left-hand end of the apparatus to the inner transfer track means 41 at the right-hand end of the apparatus, terminating in downwardly sloped extensions 42, 42 as in the case of the apparatus shown in Figs. 1 and 2. The ends of the lower rails 13, 13 at the right-hand end of the apparatus terminate in the vicinity of the inner transfer track means 41, where they merge with upwardly curved extensions 48, 48 as shown in Figs. 4 and 7.

In the apparatus shown in Figs. 4 to 8 inclusive, the other pair of lower rails 113, 113 terminate at the left-hand end of the apparatus in the vicinity of the inner transfer track means 41,

and there a pair of upwardly curved switch plates 143, 143 are provided to receive from the rails 113, 113 the wheels 22, 22 of the unconnected rail-riding means 15-15. The switch plates 143, 143 are each pivotally mounted substantially at the mid-plane by suitable supporting structure 49 such as a stub shaft mounted upon a support 50. The switch plates 143, 143 are positioned relative to the other structure and the downwardly curved ends 142, 142 of the upper rails 112, 112 similar to the arrangement of the sections 43, 43 of the switch means at the inner transfer track means 41 at the left-hand end of the apparatus shown in Figs. 1 and 2. Each switch plate 143 is provided with an upwardly extending operating arm 51, which is laterally off-set from the switch plate to lie above the rail 13 as shown in Figs. 4, 6, 7 and 8, so as to be in the path of wheel 22 of each of the connected rail-riding means 16, as indicated in dotted lines at 52 in Fig. 7.

In the apparatus shown in Figs. 4 to 8 inclusive, continuations of the pair of inside upper rails 112, 112 as indicated at 53, extend to the outer transfer track means 138 at the right-hand end of the apparatus and terminate in downwardly curved extensions 140, 140 similar to extensions 40, 40 of the upper rails 12, 12 in the structure of Figs. 1 and 2. The lower pair of rails 113, 113 also terminate at the right-hand end of the apparatus in upwardly curved extensions 139, 139 to provide parts of the transfer track means 138 similar to the upwardly curved extensions 39, 39 of rails 13, 13 at the right-hand end of the apparatus shown in Figs. 1 and 2. A gap is provided in each of the inside upper rails 112 at the inner transfer track means 41 to the left of sections 53, 53 thereof, and in each of those gaps is pivoted a switch plate 144 on any suitable means, such as a stub shaft 145 suitably supported on fixed structure at 54. Each switch plate 144 is provided with an upwardly extending operating arm 55 off-set therefrom to lie over the rail 12 in the path of wheel 22 of each of the connected rail-riding means 16 and the switch plate 144 cooperates with a downwardly curved short extension of rail 112 at the transfer track means 41 to provide a bridge when the switch is closed for wheel 22 of the unconnected rail-riding means 15.

In operation of the modification shown in Figs. 4 to 8 inclusive, assuming drive in a direction to cause the pulley wheels 26, 26 to rotate clockwise, wheels 22, 22 of a connected rail-riding means 16, supporting the leading end of a particular platform 14, will ride beneath operating arms 51, 51 of switch plates 143, 143, as indicated in dotted lines at 52 in Fig. 7, causing the latter to be swung upwardly away from the ends of rails 113, 113 to permit free passage of the transverse axle 23. After the rail-riding means 16 has passed, switch plates 143, 143 the latter will drop back to the positions indicated in Fig. 7, such as by force of gravity, to be interposed in the paths of wheels 22, 22 of the trailing unconnected rail-riding means 15. Thus, as the connected rail-riding means 16 is being pulled up along upwardly curved extensions 39, 39, the unconnected rail-riding means 15 will be caused to ride up along switch plates 143, 143 by lifting levers 37, 37 and then transferred over to the downwardly curved extensions 142, 142, finally to be guided to the pair of inside upper rails 112, 112.

In reverse motion along the upper track 10 the unconnected rail-riding means 15 will thus lead the connected rail-riding means 16 of a par-

ticular platform 14 and, with switch plates 144, 144 closed, the wheels thereof will continue on across the sections 53, 53 of the pair of inside upper rails 112, 112 to the outer transfer track means at 138. At the latter, the unconnected rail-riding means 15 will be lowered by the leading levers 37, 37 arranged in front of the transverse axle 121 at relatively the same speed as the connected rail-riding means 16 is lowered by the endless cables 25, 25 at the inner transfer track means 41, first down along the downwardly curved extensions 42, 42 of the pair of outside upper rails 12, 12, and then down along the upwardly curved extensions 48, 48 of the pair of outside lower rails 13, 13. The connected rail-riding means 16 is permitted to travel down the transfer track means at 41 by virtue of fact that the wheels 22, 22 thereof move forward beneath the operating arms 55, 55 of the switch plates 144, 144, thus lifting the latter, as shown in Fig. 7. After that connected rail-riding means 16 has passed down to its inner transfer track means at 41, switch plates 144, 144 are permitted to return to their initial positions, such as by force of gravity, so as to close the gaps in the pair of inside upper rails 112, 112.

Following this action, the connected rail-riding means 16 of a particular platform 14 will now have its wheels 22, 22 located on the pair of outside lower rails 13, 13 and leading the unconnected rail-riding means 15, having its wheels arranged on the pair of inside lower rails 113, 113, so that the action may be repeated with continued operation of the apparatus, which is the same for each of the successively arranged platforms therein. It will thus be seen that in this form of the apparatus of the present invention the switches are operated by the connected rail-riding means of each platform to permit free passage therebeyond of that rail-riding means, and that force of gravity closes the switches for the unconnected rail-riding means of the same platform. Of course, it will be understood that other suitable structure mounted on the platform may be employed to operate those switches.

The apparatus of Figs. 4 to 8 inclusive, may be operated in the reverse direction, since in such case, each connected rail-riding means 16 can be caused to open the switches for free passage by pushing against the rear sides of the switches, which after such passage will fall by force of gravity to the closed positions to handle the unconnected rail-riding means 15.

It will be noted that the employment of a plurality of dual rail structures, as proposed in the apparatus of Figs. 4 to 8 inclusive, will somewhat simplify the switch mechanisms while assuring the same desired functioning and it is to be understood that insofar as the novel transfer track means for positive guidance and support of the platform-supporting trucks at both ends thereof is concerned, switches may be eliminated by providing suitable short gaps in lateral and transfer track means at certain of their junctures to permit free and selective passage of track-riding means in the present locations of the switches where needed.

It will thus be seen that the apparatus of the present invention provides positive guidance and sure support for the platform supporting means substantially at all times and in all positions, so that the apparatus is suitably adapted to the handling of weighted objects, such as automobiles. Thus the apparatus in any of the disclosed

forms, or a variance thereof that may readily occur to those skilled in the art, is efficiently adapted to compact parking of cars with effective conservation of space. In fact, two of such apparatus may be stacked one above the other with an approach and discharge ramp for one located above the other to provide four tiers of lateral banks at parking platforms.

From the foregoing, it will be understood that the apparatus of the present invention efficiently attains the objects set forth above, in addition to those made apparent from the preceding description, and, since certain changes may be made in the above construction and different embodiments of the invention could be made without departing from the scope thereof, it is intended that all matter contained in the above description or shown in the accompanying drawings shall be interpreted as illustrative and not in a limiting sense.

It is also to be understood that the following claims are intended to cover all of the generic and specific features of the invention herein described, and all statements of the scope of the invention which, as a matter of language, might be said to fall therebetween.

Having described my invention, what I claim as new and desire to secure by Letters Patent is:

1. A conveyor apparatus for heavy loads comprising, in combination, upper and lower lateral track means each comprising two pairs of transversely spaced rails with those of one pair located inside those of the other and with the inside pairs being shorter than the outside pairs at one end of the apparatus and longer at the other end, two sets of rail-riding means with those of one set adapted to ride on said pairs of inside rails and those of the other set adapted to ride on said pairs of outside rails, a plurality of successively arranged platforms to be supported by and transported in one direction along one of said track means and then back along the other with each platform supported at one end thereof by rail-riding means of one set and at the other end thereof by rail-riding means of the other set, longitudinally spaced apart inner and outer transfer track means at each end of the apparatus each comprising a pair of rail structures with one associated with said pairs of inside rails and the other associated with said pairs of outside rails and extending substantially continuously along paths between said upper and lower track means whereby the inner transfer track means at one end of the apparatus is adapted to guide by substantially continuous contact the rail-riding means of one of said sets from the inside pair of rails of one of the lower and upper lateral track means to the same pair of the other lateral track means, and the inner transfer track means at the other end of the apparatus is adapted to perform a similar function for the rail-riding means of the other set with respect to said pairs of outside rails, driven flexible endless means connected at spaced points to each of the rail-riding means of one of said sets with those of the other set unconnected thereto, means guiding said endless means along said upper and lower track means and the inner transfer track means at one end of the apparatus and the outer transfer track means at the other end, other driven means to support and move the rail-riding means of said unconnected set along the remaining transfer track means at both ends of the apparatus substantially at the same rate of speed of the connected set of rail-riding means along their trans-

fer track means, switch means at ends of said inner transfer track means with one located at one end of the apparatus adjacent the upper track means and the other located at the other end adjacent the lower track means adapted alternately to guide and support rail-riding means of one set and to permit passage of rail-riding means of the other set, switch operators for said switch means, and a plurality of operating means each associated with and connected to one of said platforms to move therewith automatically successively to operate said switch operators during platform motion.

2. The conveyor apparatus for heavy loads as defined in claim 1 characterized by the provision of said switch means in the form of rail sections which when in closed positions substantially fill gaps in one of the two tracks provided by said inside and outside rails and their associated transfer track rail structures for substantially continuous guidance and support of said rail-riding means along their respective tracks.

3. The conveyor apparatus for heavy loads as defined in claim 2 characterized by the provision of one of said switch means as a pair of transversely spaced rail sections in the upper lateral track means beyond the junction with the inner transfer track rail structures at one end and the other of said switch means as another pair of transversely spaced rail sections in the other inner transfer track rail structures at the other end in the vicinity of the junction thereof with said lower lateral track means.

4. The conveyor apparatus for heavy loads as defined in claim 3 characterized by the provision of means rigidly tying together the two switch

rail sections in each of said pairs simultaneously to open similar gaps in the upper track means and simultaneously to divert similar sections of transfer track means from the lower track means.

5. The conveyor apparatus for heavy loads as defined in claim 4 characterized by the provision of each of said two switch means in the form of a pivotally mounted structure adapted to be swung upwardly to an open position by any one of said switch operating means and when freed from the latter to be permitted to fall to closed position.

6. The conveyor apparatus for heavy loads as defined in claim 5 characterized by the provision of each of said transfer track means as a pair of transversely spaced rail structures each comprising a downwardly sloped section extending from the vicinity of said upper track means to at least the vicinity of a mid-plane between the upper and lower track means and an upwardly sloped section extending from the vicinity of the lower track means to at least the vicinity of the mid-plane with the upwardly sloped section located beyond the downwardly sloped section nearer the end of the apparatus a distance sufficient to permit passage therebetween of rail-riding means.
